WILHELM O. TH. VAN TIENEN, OF ROTTERDAM, NETHERLANDS, ASSIGNOR TO DE BATAAFSCHE PETROLEUM MAATSCHAPPIJ, OF THE HAGUE, NETHERLANDS, A CORPORATION OF THE NETHERLANDS.

TREATMENT OF ACID TAR.

1,000,646.

Specification of Letters Patent. Patented Aug. 15, 1911.

No Drawing.

Application filed October 21, 1910. Serial No. 588,303.

To all whom it may concern:

Be it known that I, WILHELM OTTO THAARUP VAN TIENEN, a subject of the Queen of the Netherlands, residing at Claes 5 de Vrieselaan 156, Rotterdam, Kingdom of the Netherlands, have invented a certain new and useful Improved Treatment of Acid Tar, of which the following is a specification.

10 The present invention relates to a method of recovering oils which have completely or partially passed into other combinations (chiefly sulfonic acids) in the treatment of mineral oils or distillates of such oils and 15 the like, nearly the whole of the acid used for the treatment being recovered at the same time.

In the various methods for purifying mineral oils and distillates therefrom, concentrated sulfuric acid is mixed with the crude oil and this mixture continuously stirred and, under some conditions, heated. If now the mass is left to itself, two layers are formed of which the upper layer consists of purified oil (illuminating oil) and the other of a mixture of sulfonic acids formed by the action of the sulfuric acid on aromatic and unsaturated hydrocarbons, which mixture constitutes the so called acid 25 tar. In the reaction of aromatic and unsaturated hydrocarbons with sulfuric acid to form sulfonic acids, water is liberated. Since this reaction is reversible, it has been attempted, by introducing steam, to re-convert the sulfonic acids into heavy hydrocarbons and sulfuric acid. This has not led to an economical result; since the yield of recovered hydrocarbons is too small. It is true that the steam carries along with it the 30 greater part of the hydrocarbons, but the consumption of steam is too costly. Moreover the sulfuric acid liberated is impure and cannot be concentrated without fundamental regeneration. I have discovered that the reversal of the said reaction yields commercial products if instead of steam, a certain proportion of water is added to the sulfonic acids and the mixture is heated under pressure. In this manner the sulfuric acid is 35 obtained sufficiently diluted and clean, and can be very well concentrated without previous regeneration, while the heavy hydrocarbons also separate in a pure state.

According to the invention a certain pro-

portion of water, previously determined in 55 relation to the kind of sulfonic acids to be treated, the excess of sulfuric acid mixed with the acid tar and the degree of dilution thereof, is added to the acid tar. This mixture of water and acid tar is then heated in 60 a closed vessel to about 140°-165° C. under a pressure of about seven atmospheres. The duration of the heating depends on the kind of acid tar, and ranges from a quarter of an hour to two hours. 65

In practicing the invention, therefore, a predetermined quantity of water is added to the sulfonic acids and then the mixture is heated in a closed vessel to about 140°-165° C. and at a pressure of about seven atmospheres. 70 The hydrocarbons and sulfuric acid are only regenerated from the mixture if, the other conditions (temperature and pressure) being favorable, the sulfuric acid present or formed, diluted by the quantity 75 of water added, has a certain concentration. The acid tar is therefore heated with a quantity of water which brings the sulfuric acid present and formed, to the desired degree of concentration. The sulfonic acids 80 are then split up, if the temperature and pressure conditions are right, into the original aromatic hydrocarbons and sulfuric acid. Three layers are formed, of which the uppermost consists of pure hydrocarbons, 85 which can be used directly, after washing with water, as motor oils and for other purposes, the lowest layer consists of pure diluted sulfuric acid capable of direct concentration, which can be used again for purifying mineral oils or their distillates, while 90 between these two layers there is formed a very thin layer, which contains small residues of acid and resinified tar. Owing to this stratification the various products can 95 easily be separated.

The proportion of water to be added to the acid tar as mentioned above, depends on the kind of hydrocarbons present in the tar as sulfonic acids, because these hydrocarbons determine each by its composition the proportion of sulfuric acid combined in the sulfonic acid and also the proportion of free acid present. In each acid tar therefore the proportions of combined sulfuric acid 100 (reckoned as acid of 1,841 specific gravity equal to 66° Baumé) and free sulfuric acid 105 (reckoned as acid of 1,692 specific gravity

equal to 59° Baumé) are ascertained and the quantity of water necessary for sufficient dilution is then calculated. The excess of free acid remaining from the acid of 5 66° Baumé specific gravity originally used has been diluted to 59° Baumé specific gravity by the water liberated during the sulfonation. For the reaction which is to occur in the pressure vessel, the quantity of 10 water added must be such as to dilute this excess of acid and that liberated by the water from the sulfonic acids, to 52° Baumé specific gravity. An acid of the specific 15 gravity last named cannot re-sulfonate the oils. The quantity of water is therefore so reckoned that the acid present after the action has a specific gravity of 1.565 specific gravity equal to 52° Baumé only to insure that the acid shall not have a sulfonating 20 action. It is not advisable to add a larger proportion of water, since this would dilute the acid unnecessarily and increase the cost of subsequent concentration.

25 The following example illustrates the invention:—An acid tar which contains for each 100 parts by weight 43 parts by weight of combined acid of 66° Baumé specific gravity and 14 parts by weight free acid of 59° Baumé specific gravity, must be heated 30 for two hours at 165° C. and 7 atmospheres pressure with 23.3 parts by weight of water.

The liquid separates into two layers, of which the one consists of the regenerated oils and the other of sulfuric acid of about, at the most, 52° Baumé specific gravity. 35 These two layers can be separated in any known manner and the acid concentrated to 66° Baumé specific gravity. In this manner there are obtained 38.7 parts by weight heavy oils (aromatic and unsaturated hydrocarbons) and 51.3 parts by weight acid of 66° Baumé specific gravity after concentration. 40

I claim:

A method of recovering hydrocarbons and 45 sulfuric acid from acid tar which consists in mixing the acid tar with a proportion of water sufficient to dilute the acid which will be liberated by the action of the water and the free acid existing in the acid tar, to a 50 specific gravity of not more than 52° Baumé and heating the mixture at a pressure of about 7 atmospheres and at a temperature of about 140°—165° C.

In testimony whereof I have hereunto set 55 my hand in presence of two subscribing witnesses.

WILHELM O. TH. VAN TIENEN.
